UNITED STATES PATENT OFFICE.

ALFRED G. BUTLER, OF VALLEY FORD, WASHINGTON.

DEVICE FOR CHECKING HORSES.

1,155,403.

Specification of Letters Patent.

Patented Oct. 5, 1915.

Application filed April 3, 1915. Serial No. 19,029.

To all whom it may concern:

Be it known that I, ALFRED G. BUTLER, a citizen of the United States, residing at Valley Ford, in the county of Spokane and 5 State of Washington, have invented certain new and useful Improvements in Devices for Checking Horses, of which the following is a specification.

This invention relates to devices for checking horses, and with regard to certain more specific features thereof to devices adapted to be thrown in and out of operative position at will, either for hitching a horse while the vehicle is temporarily at rest, or for stopping runaway horses.

One of the objects of the present invention is to provide a practical and self-contained device which may be easily and quickly mounted upon any vehicle without 20 material alterations.

A further object is to provide a device of the above character having few parts which will be cheap to manufacture and install.

A further object is to provide a simple device of the above character which will be reliable and efficient in use and operation at all times and not likely to get out of order or wear out.

Other objects will be in part obvious from 30 the annexed drawings and in part indicated in connection therewith by the following analysis of this invention.

This invention accordingly consists in the features of construction, combination of 35 parts and in the unique relations of the members and in the relative proportioning and disposition thereof, all as more completely outlined herein.

To enable others skilled in the art so fully 40 to comprehend the underlying features thereof that they may embody the same by the numerous modifications in structure and relation contemplated by this invention, drawings depicting a preferred form have 45 been annexed as a part of this disclosure, and in such drawings like characters of reference denote corresponding parts throughout all the views, in which—

Figure 1 is an elevational view showing 50 the complete device in operative position as applied to an ordinary horse-drawn vehicle; Fig. 2 is a detail perspective view of the parts of the device in disassembled position; Fig. 3 is a sectional view with parts in 55 operative position; Fig. 4 is a detail perspective view of one form of operating lever.

In these drawings 5 designates a vehicle

having wheels 6, to the rear right-hand one of which may be attached the checking device 7.

A hand operating lever 8 is pivoted at 9 to the side of the vehicle, although a foot lever may be used if desired, and is provided with a guard 10 having notches 11 and 12 at the opposite ends thereof into which the lever 8 may drop and be held against movement. The lower end of this lever 8 is pivotally connected at 13 with a rearwardly extending rod 14 adjustably connected at its opposite end with the device 7. This device, as shown more clearly in Fig. 2, comprises a plate 15 carrying a central tubular member 16, adapted to fit over the hub of the wheel on the inner side and closely adjacent spokes 17 thereof. Fastening means, such as loops 18, may be employed for firmly 75 clamping the plate 15 in position. This plate is provided with two pawls 19, fitting in sockets and spring pressed into operative position.

Closely fitting over the tubular member 16 is a winding drum 20 provided with a groove 21, and around which a cord 22 may be wound, as between suitable flanges 23. The lower part of this member 20 is provided 85 with ratchet teeth 24 adapted to coact with the pawls 19 when moved into engagement therewith under certain circumstances, as will be hereinafter explained. Ball bearings 25 may be provided at one or both ends of 90 this member 20, in order to permit a free relative rotary and sliding movement between this member and the coacting parts, if so desired.

About the member 20 is a second tubular 95 member or casing 26 provided on its interior with flattened surfaces 27, spaced apart a distance substantially equal to the maximum diameter of the member 20. This construction permits a relative lateral movement of 100 the part 26 with respect to the part 20 on movement of the rod 14.

Lugs 28 on the inner flattened surfaces 27 of the member 26 are designed to coact with the upper flange 23 in order to move the 105 same in an axial direction to carry the pawl and ratchet mechanism into and out of engagement. This member 26 is adjustably connected with the rod 14 in any desired manner, as by means of set screws 29, or the 110 like.

A cap 30 having a collar 31 is adapted to be screwed onto the upper threaded end 32 of the member 16. The set screws 33 pass-

ing through this collar 31 are designed to engage the inner edge of the hub, thereby to securely hold the parts in position, whereby all but the member 26 will rotate with the wheel. It will thus be seen that the parts are all inclosed in a self-contained device mounted upon the inner end of the hub of the vehicle, whereby it rotates as the wheel rotates. Tight joints and threaded connection between the several parts provide a substantially dust-proof and dirt-proof construction.

The operation of this device is substantially as follows: In normal operation the lever 8 is thrown back to engage the notch 11, which causes a relative lateral movement of the member 26 with respect to the member 20 along under the axis of the wheel and one of the lugs 28 coacts with the flange 23 to move the same axially and carry the pawl and ratchet mechanism out of engagement. The wheel is therefore permitted to rotate freely with respect to the member 20, when in normal position without noise. If however the horses are running away, or it is desired to hitch them while the vehicle is at rest, the lever 8 is thrown forward into the notch 12, causing a rearward movement of the rod 14, and the other lug 28 to coact with the flange 23 and force the ratchet of the drum 20 into engagement with the spring-actuated pawls 19, thus firmly locking the drum to the plate 15. A rotation of the latter with the wheel will cause a corresponding rotation of the drum to wind up the cord 22, it of course being understood that the free end of the cord 22 is attached after passing through suitable pulleys on the vehicle to the bridle of the horse. This winding of the cord and pulling on the bridle will soon stop the horse and cause a natural tendency of the horse to back. This immediately relieves the pull but will not rewind the cord. Even if the horse continues to back there will be no reverse winding of the cord as the pawls slip quietly over the ratchet. When the horse is under control the lever is moved to release position and the cord pulled out to its normal position, the drum being free to unwind under such conditions.

It is thus seen that the present invention provides a simple and practical device adapted to accomplish, among others, all of the advantages and objects above set forth.

Without further analysis, the foregoing will so fully reveal the gist of this invention that others can by applying current knowledge readily adapt it for various applications without omitting certain features that, from the standpoint of the prior art, fairly constitute essential characteristics of the generic or specific aspects of this invention,

and therefore such adaptations should and are intended to be comprehended within the meaning and range of equivalency of the following claims:

Having thus described my invention what I claim as new and desire to secure by Letters Patent is:

1. In a device of the character described in combination, a member adapted to fit over the hub of one of the wheels of a horse drawn vehicle and rotate therewith, a winding drum loosely mounted on said member, a casing therefor, a flexible connection adapted to be wound on said drum having its free end connected with the bridle of the horse, a pawl and ratchet mechanism for connecting said drum with said first mentioned member, and means for moving said drum axially by shifting said casing transversely to complete the connection through said pawl and ratchet mechanism.

2. In a device of the character described in combination, a cylindrical member adapted to fit over the hub of one of the wheels of a horse drawn vehicle and be clamped thereto to rotate therewith, a winding drum fitting over said member and provided with a flange, a flexible member adapted to be wound on said drum and having its free end connected with the bridle of the horse, a tubular sleeve loosely fitting over said winding drum, cams carried by said sleeve adapted to coact with the flange on said drum for moving the same axially as said sleeve is moved laterally, and a pawl and ratchet mechanism between said drum and the plate adapted to lock said parts together.

3. In a device of the character described in combination, a cylindrical member adapted to fit over the hub of one of the wheels of a horse drawn vehicle and be clamped thereto to rotate therewith, a winding drum fitting over said member and provided with a flange, a flexible member adapted to be wound on said drum and having its free end connected with the bridle of the horse, a tubular sleeve loosely fitting over said winding drum, cams carried by said sleeve adapted to coact with the flange on said drum for moving the same axially as said sleeve is moved laterally, a pawl and ratchet mechanism between said drum and the plate adapted to lock said parts together, and means operable from a point adjacent the driver's seat adjustably connected with said sleeve for moving the same laterally.

In testimony whereof I affix my signature in presence of two witnesses.

ALFRED G. BUTLER.
